ATTORNEY.

UNITED STATES PATENT OFFICE.

LINCOLN HOWARD, OF RALSTON, NEBRASKA.

COMBINATION COAL AND WOOD HEATING-STOVE.

993,300.

Specification of Letters Patent. Patented May 23, 1911.

Application filed June 17, 1910. Serial No. 567,440.

To all whom it may concern:

Be it known that I, LINCOLN HOWARD, a citizen of the United States, residing at Ralston, in the county of Douglas and State 5 of Nebraska, have invented certain new and useful Improvements in a Combination Coal and Wood Heating-Stove, of which the following is a specification.

The object sought by me in the invention 10 of the improved stove hereinafter described is to provide a stove from which increased heat is obtained from a decreased quantity of fuel and in which either wood or coal can be used as a fuel.

15 I accomplish my object by the construction shown in the accompanying drawings, in which—

Figure 1 is a longitudinal sectional elevation of the stove, the base, fire pot and drum 20 broken away to show the interior arrangement; Fig. 2 is a top view of the fire pot, grates, and a flange or projection at the rear of the fire pot with openings therein, and Fig. 3 is a sectional view of the fire pot, the 25 rear of the base of the stove, a casting seated therein and a segmental opening for the passage of hot air.

Similar letters refer to similar parts in the several views.

30 A is a fire pot cast in an inverted conical shape to assist in radiating heat to the floor.

B shows a flange, projecting rearward from the fire pot, the same being provided with openings b b . . . Said fire pot flange 35 is also provided underneath its edge with a groove b'.

C is a casting spaced from the rear of the fire pot. D is the base of the stove, D' D' are the grates therein and d is a segmental 40 opening into said base. Said casting C is seated in the top edge of said base, as shown in Fig. 1, its top edge being held in said groove b'. Said casting forms a passage at the rear of said fire pot through which pre- 45 heated air draws through openings b b . . . , passes downward and thence through said segmental opening d into the base of the stove from which base it is drawn up through the grates into the fuel. The sheet 50 iron body E of the stove is, preferably, joined to the top of the fire pot, as shown in Fig. 1 at e. F is a casting which forms an inner wall of a draft passage through which cold air entering the stove at draft F'

passes to the rear of the stove, part through 55 ports f f . . . into the combustion chamber above the fire pot, the balance through said openings b b . . . into the pre-heated air passage formed by casting C and thence down through said segmental opening d into 60 the base of the stove. The special object of casting F is to carry the cold air entering the stove at said draft F' around the stove the longest possible circuit so that it will be 65 heated to the highest degree possible before it is admitted into the combustion chamber. Said casting F is seated in the upper edge of the fire pot and is usually composed of two or more sections; it is preferably corrugated, except at the edges where it joins the 70 sheet iron body and the fire pot of the stove. The upper edge of said casting lies flat against said sheet iron body. The purpose in casting it corrugated is to secure greater 75 strength and heating surface.

H is an incurve extending horizontally around casting F. The rear section of said casting is provided with a seat J in said incurve H to support a baffle plate K. The air admitted through draft F' passes 80 through said incurved draft passage and becomes highly heated in passing to the rear of the stove, the larger part passing thence through a plurality of ports f f . . . in the lower part of casting F into the combustion 85 chamber under baffle plate K where it is forced to mingle with and burn the gases and smoke coked out of the fuel, while the smaller part passes down through openings b b . . . , as shown in Figs. 1 and 2, into 90 and through the hot air passage formed by casting C and through segmental opening d, as shown in Figs. 1 and 3, into base D, much of it passing thence up through grates D' D' to start and keep up the coking and gas 95 making process. Casting F is kept at a high temperature by means of a hot blast from the rear of the stove, and the temperature of the air while passing through it continues to increase. The volume of air 100 passing through said draft passage is greatly expanded by its rise in temperature and rushes into the combustion chamber with great force. By means of the baffle plate K this pre-heated air is deflected toward the fire and forced to mingle with the combustible smoke and gases arising from the fuel. That part of the pre-heated air 105

2
passing downward through the base is only sufficient to keep the fire alive and keep up the coking and gas making process.

What I claim and desire to secure by Letters Patent, is,

The combination in a wood and coal heating stove, of a base having a segmental opening in the rear part of the top, a fire pot of inverted frusto conical shape, duplicate grates therein, a horizontal flange on the top edge of the rear of the fire pot provided with a plurality of openings and with a curved groove underneath the edge thereof; a curved casting seated in the side of the fire pot and on said base outside said segmental opening its top end engaging with said groove, the central part of said casting being spaced from said fire pot forming therewith a hot air passage, a sheet iron body, a corrugated incurved casting seated on the fire pot and a draft door therefor, said incurve in said casting and the stove

body forming a passage for the air entering said draft door the ports above the fire pot through the rear part of the incurved casting forming outlets from said passage into the combustion chamber through which a part of the pre-heated air from said incurved passage passes into the combustion chamber while the balance is drawn down the rear hot air passage formed by said curved casting into said base to pass up into the fuel, and a baffle plate to force the pre-heated air from said ports to mingle with and burn the gases and smoke coked out of the fuel, substantially as shown and described.

In testimony whereof I affix my signature in presence of two witnesses.

LINCOLN HOWARD.
